UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 30,804, dated May 16, 1899.

Application filed April 6, 1899. Serial No. 712,016. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover, of which the following is a specification, reference being had to the accompanying drawings, forming part thereof, in which—

Figure 1 is a top or plan view of a manhole-cover, showing the particular shape or configuration of the cover of my design; and Fig. 2 is a vertical sectional view on the line $x-x$ of Fig. 1.

The two views are deemed essential to a proper or full disclosure and illustration of the design for and in a manhole-cover of my invention.

As illustrated in the drawings, the leading feature of my design consists of the cover A, substantially dish shape in cross-section, with the base a upwardly or convexly curved inward toward the middle of the bottom from the periphery. The base a is provided with an outwardly flaring surrounding wall a' , merging into an angular rim a^2 , forming an offset a^3 on the inner side of the cover about the rim portion, in which the surrounding in-

ner surface of the offset portion of said rim is made to taper from the base a^4 of the offset of the rim to the top of the rim, so as to provide a greater surface in cross-section from the base to the top a^5 of the rim a^2 of the cover A. Opposite each other in the offset rim portion a^3 are provided inner curved projections c and substantially semicircular recesses c' , with openings c^2 about said recesses and extending into the body of the offset portion a^3 of the rim a^2 , as illustrated in Fig. 1. The under side a^6 of the cover A is provided with a central annular rib a^7 , with a series of radial tapering wings or arms a^8 extending therefrom and forming part of the bottom of the cover.

Having thus described my invention, what I claim as new, and desire to secure by Letters Patent, is—

The design for a manhole-cover, substantially as herein shown and described.

In testimony whereof I have hereunto set my signature in the presence of two subscribing witnesses.

THOMAS P. GREGER.
